**SYSTEM FOR ESTABLISHING A PLURALITY OF
FLUID PRESSURE LEVELS**

Drug and Chemical Company, Los Angeles, Calif., a
corporation of Delaware

Filed June 15, 1964, Ser. No. 375,157
5 Claims. (Cl. 137—115)

This invention relates to a novel system for establishing a plurality of fluid pressure levels and relates more specifically to a novel arrangement of differential pressure regulating means for establishing at least two, but preferably three pressure levels. The novel arrangement of the differential pressure regulators is particularly useful with hydraulic fluids which are employed to drive larger units such as single or double acting intensifiers. In high pressure technology, various uses are made of intensifiers of the foregoing type, although any pump that is driven by hydraulic fluid can be used in association with the novel system of this invention where the concept herein is applicable.

In prior art systems where use is made of a hydraulic fluid to drive a low pressure piston face which acts on a smaller piston face to compress a fluid and discharge it into a high pressure process area, various arrangements for creating and maintaining hydraulic fluid flows to the low pressure piston faces have been suggested and used. Such arrangements have included a differential pressure regulating valve in association with other flow diverting systems such as compensators and/or pilot valves. In these arrangements of the foregoing valve systems for diverting hydraulic fluids while pressure levels of one type or another have been established, usually the excess energy in each of the pressure levels is not utilized since this is by-passed to a reservoir and consequently such systems are inefficient. It would be desirable to provide improvements in such systems whereby a plurality of hydraulic fluid pressure levels could be established and the excess flow from the higher levels could be diverted to the next lower level, thus making efficient use of the energy contained therein.

It is an object of this invention to provide a novel arrangement of valve means for establishing a plurality of hydraulic fluid pressure levels.

It is a further object of this invention to provide a novel arrangement of differential pressure regulating means for use in hydraulic actuated systems.

It is a still further object of this invention to provide a system for establishing at least two, but preferably three different hydraulic fluid pressure levels which can be used for driving hydraulic intensifier units.

This invention provides two differential pressure regulators embodying therein a resilient force and a piston, the said piston and resilient force being capable of actuation by a hydraulic fluid supplied via inlet and outlet ports and conduits associated therewith for the establishment of a plurality of hydraulic fluid pressure levels.

The differential pressure regulators are arranged in such a manner, according to this invention, so that a first hydraulic differential fluid pressure level can be established across an orifice in a conduit used for delivering hydraulic fluid at a pressure level to drive an intensifier system, for example, and flow in excess of that required for said first pressure level is by-passed to a second hydraulic fluid pressure level. In like manner, according to the invention, flow in excess of that required for maintaining the second pressure level is by-passed to a third level and arrangements can be provided for ultimately diverting to the sump any flow in excess of that required for maintaining said third pressure level. As one skilled in this

art will readily understand, work can be performed by the second and third hydraulic fluid pressure levels by proper diversion thereof to areas where they are needed.

In the ensuing description of this invention, it will be understood that the terms "hydraulic fluid," "fluid," "oil" or "non-compressible fluid" will be used synonymously. "Piston" or "spool valve" with reference to the units in the differential pressure regulating valve are likewise intended to have a similar meaning, while a "resilient force" or "resilient force constant" are to be deemed equivalent to a spring force or spring force constant.

Reference is made to the attached drawing which represents the preferred arrangement of two differential pressure regulating valves and the manner in which they are associated for operation as noted herein.

With brief reference to the drawing, numerals 1 and 31 represent enclosed cylindrical chambers which are adapted to contain therein a slideable piston or spool valve 2 and 32. The spool valves as indicated slidably contact the surface of the chambers and move back and forth therein according to certain pressures acting thereon which will be indicated hereinafter. At one end of each of the valves 1 and 31 is located spring forces 3 and 33. These spring forces are usually of a fixed amount or force constant and abut the valve faces 4 and 34.

Within the body of the chamber, spool spindles 5 and 35 form an integral unit with the other spool valve faces 6 and 36. It will be seen that chambers 7 and 37 are provided between the two spool valve faces for circulation of a hydraulic fluid such as an oil. At either end of the cylindrical chambers 1 and 31 is located conduit ports 8 and 9 and 38 and 39 respectively. An inlet port 10 and corresponding inlet port 40 on chambers 1 and 31 are also provided for introduction of hydraulic fluid to chambers 7 and 37. Outlet ports 11 and 41 are likewise provided in chambers 1 and 31 respectively for discharge or by-pass of hydraulic fluid. Between the two cylindrical chambers, conduit 12 is provided and this conduit leads to conduit 13, as well as conduit 14, check valve 15 and thence to conduits 16 and 17.

Located within cylindrical chambers 1 and 31 are stops 18 and 18a, 19 and 19a, and 42 and 42a and 43 and 43a which function to limit the movement of the slideable spool valves so that they are not opening or closing the wrong port channels. Thus, in chamber 1, spool valve 2 moves to the right and abuts against stops 19 and 19a at which point inlet port 10 is opened. In its normal position, the spring force of spring 3 forces the spool valve 2 against the stops 18 and 18a to thereby close port 10. The spring and stops in chamber 31 function similarly. It will be noted that the springs 3 and 33 are located at opposite (effective) ends with respect to each other in the two differential pressure regulating valves.

The differential pressure regulating valves can be provided with a main conduit 60 for introduction of hydraulic fluid to actuate the spool valves in chambers 1 and 31 and thereby make it possible to establish a series of pressure levels. Hydraulic fluid is directed through flow control valve 61 and onto conduit 62 where by virtue of pressure regulating valve or chamber 1, the pressure in line 60, P_{1a} , is established relative to the hydraulic reference pressure level P_1 . In the arrangement illustrated in the drawing, fluid in excess of that required for maintaining said P_{1a} pressure level is diverted from conduit 60 to conduit 63 and thence to conduits 64 and 65.

As illustrated, conduit 62 can be tapped to provide conduit 66, which serves as a reference pilot pressure for at least one of the valves, as will be explained below. Constrictions 67 and 68 can be provided in conduits 69 and 70 which lead to ports 8 and 38 respectively. The operation of this novel system for establishing a plurality of pressure levels will now be described.

A hydraulic fluid is introduced as illustrated in the drawing through conduit 60, and a given percentage of the volume flowing therethrough passes through flow control valve 61 to conduit 62 and on to establish a reference P_1 pressure level. The flow in excess of that required for maintaining said first hydraulic fluid pressure level P_{1a} is diverted via conduits 63, 64 and 65. Port 10, which is normally kept closed by spool valve 2 will open, thus spilling into chamber 7 due to the fact that the fluid pressure from conduit 64 exerted on face 6 of the spool is greater than that of pressure level P_1 and the spring force constant 3 which is exerted on the opposite face of the spool valve 4. When the fluid pressure level P_1 plus the spring force constant 3 acting on spool valve face 4 exceeds the fluid pressure from conduit 64 acting on face 6, then the spool valve will slide to the left and close inlet port 10. The fluid pressures acting on the spool valve faces can also come to a dynamic balance and continuously throttle the hydraulic fluid.

By-passed fluid from chamber 7 flows to conduit 12 through outlet port 11 and thence to conduits 13 and 14, through check valve 15 and conduits 16 and 17. In this arrangement, valve 31 acts opposite with respect to valve 1, that is, the valve is normally open rather than closed and the spring force constant is located at the opposite end with respect to that of valve 1. In this case, when the pressure of the fluid in line 17 plus the force of spring 33 acting on face 34 is less than the P_1 pressure level acting through conduit 70, the spool valve 32 will move to the left to close inlet port 40. When the pressure level P_1 acting through conduit 70 on spool valve face 36 becomes less than the spring force 33 and the fluid pressure acting through conduit 17, the spool valve will slide to the right and open inlet port 40.

It will be noted from the foregoing that in the absence of any fluid pressures, the valves 1 and 31 are normally closed and normally open respectively. The dynamic balance of the spool valves in each case is determined by the sum of forces acting on its faces so that in this manner, in addition to the first fluid pressure level P_{1a} , fluid pressure levels P_2 and P_3 can be established as described below. Thus, fluid pressure level P_2 is established by diverting flow from conduit 12 to conduit 13 when valve 31 is closed. This pressure level P_2 is always maintained below the P_1 pressure level (which is controlled by the downstream process side) by at least the spring force constant in force per unit area of spring 33. It can be seen, therefore, that it is the arrangement of the valves and the value of the spring force constant 33 which establishes this difference in the two fluid pressures P_1 and P_2 . The P_3 pressure level can be established by the outlet flow of valve 31 through port 41 and conduit 41a. A relief valve 41b can be provided in association with this conduit to establish the P_3 fluid pressure level. A particular use for these differential pressure regulating valves as arranged and illustrated in the attached drawing is disclosed in co-pending application Serial Number 372,266, filed June 3, 1964 now Patent No. 3,234,882 for use in driving two single acting intensifiers in a "painless" method.

From the above description of the preferred arrangement of the differential pressure regulating valves, it will be seen that the reference pressure level P_1 which can be used to drive a piston, for example, is also used in this case as the pilot or reference pressure for actuation of spool valves 2 and 32, while the P_{1a} and P_2 are the pressures being controlled. It can also be seen that in this preferred arrangement of the valves, the flow in excess of that required to maintain the fluid pressure level P_{1a} is by-passed and is used to establish a second fluid pressure level P_2 via the valve arrangements herein and flow in excess of that required to maintain said second fluid pressure level P_2 is further by-passed via the second valve and used to establish a third fluid pressure level P_3 as described hereinabove and illustrated in the drawing. 75

Although it is indicated above that one use for the novel arrangement of the valves herein is in driving a hydraulic intensifier, other uses for such an arrangement include the driving of various other units requiring a plurality of driving forces as will be understood by those skilled in this art.

While the foregoing represents a preferred embodiment and arrangement of the pressure differential regulating valves of this invention, resort can be had to innovations and changes which fall within the scope of the invention and the coverage of the appended claims.

What is claimed is:

1. In combination, a first and second differential pressure regulating valve, each of said valves comprising an enclosed cylindrical chamber, a slideable spool valve therein, a fixed resilient force opposing one end of said spool and abutting on one end of said chamber in said first valve, a given resilient force opposing the opposite end of the spool in the second chamber with respect to the spool in the first chamber and abutting on said opposite end of said second chamber, a conduit in each of said chambers for providing a reference fluid pressure for actuation of said spool valves against at least the fixed resilient forces therein, said first valve being provided with an inlet and an outlet port, said inlet port being maintained in a normally closed position by the spool valve in association with the given resilient force, said second valve being provided with an inlet and an outlet port, said inlet port being maintained in a normally open position by the spool valve in association with the given resilient force and conduit connections between the outlet port of said first valve and the inlet port of said second valve.

2. The combination of the differential pressure regulating valves of claim 1 wherein a check valve is provided in the conduit connection between said first valve outlet port and the inlet port of said second valve.

3. The combination of the differential pressure regulating valves of claim 1 wherein the given resilient forces in said first and second valves constitute fixed spring constants.

4. In combination, a first and second differential pressure regulating valve, each of said valves comprising an enclosed cylindrical chamber, a spool valve for movement in slideable contact in said chamber, a fixed spring force constant opposing one end of said spool and abutting on one end of said chamber in said first valve, a fixed spring force constant opposing the opposite end of the spool in the second chamber with respect to the spool in the first chamber and abutting on said opposite end of the second chamber, a conduit in each of said chambers for providing a reference fluid pressure for actuation of said spool valves, a conduit in the opposite end of each chamber for providing a fluid pressure which is to be controlled, said first valve being provided with an inlet and an outlet port, said inlet port being maintained in a normally closed position by the spool in association with the given spring force, said second valve being provided with an inlet and an outlet port, said inlet port being maintained in a normally open position by the spool in association with the given spring force, and conduit connections between the outlet port of said first valve and the inlet port of said second valve.

5. The combination of the pressure regulating valves of claim 4 wherein the conduit connection between the outlet port of said first valve is associated with the conduit of the second chamber for providing a fluid pressure which is additive to that of the spring force for actuation of the spool valve in said second chamber.
